UNITED STATES PATENT OFFICE.

WALTER R. FURNESS, OF PHILADELPHIA, PENNSYLVANIA, ASSIGNOR TO
THE SPORTING LIFE PUBLISHING COMPANY, OF PENNSYLVANIA.

DESIGN FOR A TARGET.

SPECIFICATION forming part of Design No. 27,280, dated June 29, 1897.

Application filed April 7, 1897. Serial No. 631,177. Term of patent 31 years.

To all whom it may concern:

Be it known that I, WALTER R. FURNESS, a citizen of the United States, residing in the city and county of Philadelphia, State of Pennsylvania, have invented and produced a new and original Design for Targets, of which the following is a specification, reference being had to the accompanying drawings, showing a part thereof.

The leading feature of my design for a target is a bull's-eye with wings extending therefrom.

Figure 1 represents a plan view of a target embodying my design. Fig. 2 represents a section thereof on line x x , Fig. 1.

In the drawings, A represents the border of a target.

B designates the bull's-eye of the target.

C designates wings extending from said bull's-eye. 20

What I claim is—

The design for a target, substantially as shown and described.

WALTER R. FURNESS.
